UNITED STATES PATENT OFFICE.

AUGUST F. KRAEMER, OF PROVIDENCE, RHODE ISLAND, ASSIGNOR TO LOUIS STERN COMPANY, OF PROVIDENCE, RHODE ISLAND, A CORPORATION OF RHODE ISLAND.

BUCKLE.

Application filed October 29, 1928. Serial No. 315,604.

This invention relates to a buckle for fastening the ends of a wrist strap more particularly of the type for securing a wrist watch in position on the arm of the wearer; and has for its object to provide a construction for easily attaching and detaching its members by the single available hand of the wearer of the strap.

A further object of the invention is the provision of a buckle in which the construction for holding the parts together are hidden by a cover so that the buckle may be of a more attractive appearance or suitably decorated upon the surface presented.

With these and other objects in view, the invention consists of certain novel features of construction, as will be more fully described, and particularly pointed out in the appended claims.

20 In the accompanying drawings:

Fig. 1 is a top plan view of the two part strap with my buckle in position thereon.

Fig. 2 is a side elevation of the buckle with portions of the strap attached thereto.

25 Fig. 3 is a perspective view looking at the under side of the cover member.

Fig. 4 is a perspective view of the plate which has openings to receive the detents of the male part of the buckle member.

30 Fig. 5 is a perspective view looking at the underside of the male buckle member with the parts shown in Figs. 3 and 4 assembled.

Fig. 6 is a perspective view of one part 35 of the male buckle member.

Fig. 7 is a perspective view of the under side of the male buckle member showing the strap clamp thereon.

Fig. 8 is a sectional view of the two buckle 40 members in clasped position.

This invention is an improvement of my copending application, Ser. No. 274,236, filed May 1, 1928, and by my new construction the female member of the buckle which has a 45 plate with openings therein to receive the detents of the male buckle member is hidden by a cover which presents a very attractive appearance and by means of flanges on the cover this member may be guided and more easily snapped into position over the male member and detached by means of the finger-piece which also holds the parts in position and the following is a detailed description of the present embodiment of this invention illustrating the pre-

ferred means by which these advantageous results are accomplished:

With reference to the drawings, 10 designates one strap part which is provided with a loop 11 at one end thru which the other 60 strap part 12 slidably extends.

The male member of this buckle consists of a channel-shaped saddle part 13 having detents 14 extending from its surface and receives between its side walls 15 the strap 65 part 10 which is clamped in any desirable position by a cam acting gripper pivoted in the side walls 15 by trunnions 17.

The female member of this buckle forms a tip for this strap part 12 and consists 70 of a plate 18 having openings 19 therein suitably cut away as at 20 to allow resiliency of its side wall for snapping over the detents 14 of the male member to hold the buckle members together. A cover, as 75 illustrated in Fig. 3, is provided for this plate which has a sheet metal top 21 with side flanges 24 and an end flange 22 slotted as at 23 extending therefrom. The plate 18 is provided with a finger-piece 25 which extends thru the slot 23 to hold the same in position. This slot is spaced slightly from the sheet metal top wall which is accurately shaped to form a space for the reception of the detents 14 when snapped thru the plate 80 85 openings 19.

The plate is offset as at 26 so that a portion 27 will lie snugly against the top plate 21 at its other end, which portion receives the end 28 of the strap 12 to be clamped in this position by means of arms 29 extending from the cover and folded inwardly about this strap end 28. These arms have teeth 30 thereon to bite into and hold the strap in position. The offset of the plate as at 26 90 95 also provides a stop to limit the insertion of the strap 12 and assists in the assembly of the strap and buckle in the manufacture of the same.

A flange 32 may be provided at the strap 100 engaging end of the cover to assist in holding the strap in position and at the same time providing the buckle with a more finished appearance and serving to prevent a sliding movement of the plate from its position in the slot 23.

Further, in order that a proper point of bending of the arms may be provided, flanges 31 extend from the offset portion of the plate over which the arms are bent into 110

their biting and embracing relation with the strap.

It will be apparent from the above that the two part buckle which I have provided is of a construction to present an extended surface or ornamentation without the visible openings or projections thru a plate to detract the ornamental appearance which the same may have.

10 The foregoing description is directed solely towards the construction illustrated, but I desire it to be understood that I reserve the privilege of resorting to all the mechanical changes to which the device is 15 susceptible, the invention being defined and limited only by the terms of the appended claims.

I claim:

1. A separable buckle for separable strap parts, comprising two cooperating members, one carried by each of the strap parts, one member being adjustably secured to one strap part and the other member being secured to the end of the other strap part and 25 comprising a plate, cooperating means be-

tween said first member and plate for releasably locking them together, a sheet metal cover for said plate, flanges extending from said cover, one flange having a slot therein, a projection on said plate extending thru said slot to serve as a finger-piece for separating said member and also to hold said plate in position in said sheet metal cover.

2. A separable buckle for separable strap parts, comprising two cooperating members, 35 one carried by each of said strap parts, one member being adjustably secured to one strap part and the other member secured to the end of the other strap part and comprising a sheet metal cover having an end flange 40 with a slot therein, a plate within said cover spaced therefrom adjacent to said flange and offset to lie against said cover at its other end to receive on said offset portion the strap to which it is connected, and a finger-piece extending from said plate thru said slot to hold the plate in said spaced relation.

In testimony whereof I affix my signature.

AUGUST F. KRAMER.
